[57] CLAIM

The ornamental design for a small telephone keyset, as shown and described.

DESCRIPTION

FIG. 1 is a top front perspective view of a small telephone keyset showing our new design;
FIG. 2 is a rear perspective view thereof;
FIG. 3 is a fragmentary perspective view of the telephone base;
FIG. 4 is an enlarged fragmentary top plan view thereof;
FIG. 5 is an enlarged side elevation of the telephone handset, shown separately for clarity of illustration;
FIG. 6 is a bottom plan view thereof;
FIG. 7 is a top plan view thereof; and
FIG. 8 is an end elevation thereof.
